ARTIFICIAL SNOW

Charles A. Dragotta, Bergenfield, and Albert C. Cereghino, Jr., Livingston, N.J., assignors to National Dairy Products Corporation, New York, N.Y., a corporation of Delaware

No Drawing. Filed Feb. 29, 1960, Ser. No. 11,919

3 Claims. (Cl. 260—23)

The present invention generally relates to decorative compositions and, more particularly, it relates to artificial snow compositions which can be sprayed.

Various artificial snow compositions are commercially available in aerosol containers and they are widely used during the Christmas season each year. Such compositions usually comprise a flocking agent which produces snow-like material and which may be a resin or the like; a solvent or dispersant for such flocking agent; and a pressurized propellant; the composition being packaged in a pressurized can commonly known as an aerosol container. When the composition is sprayed from the container, the flocking agent takes the form of flock or snow-like particles which are directed against and which more or less adhere to the object to be decorated.

Inasmuch as one of the principal uses of the artificial snow compositions is in the decoration of Christmas trees, Christmas wreaths, windows and the like, and it is frequently desirable to be able to spray outdoors. Furthermore, the container can be subjected to cold conditions when transported from the store to the home. It is, therefore, desirable that the composition be fluid at low temperatures. In this connection, the presently available artificial snow compositions generally do not spray properly when temperatures are below about 70° F. At lower temperatures, these compositions set up so that they can not be effectively sprayed, either because the nozzle of the containers become clogged or the product becomes too viscous. Accordingly, most manufacturers of artificial snow compositions, which are dispersed by means of a propellant from an aerosol container, indicate on the container the required temperature conditions for proper use of the composition. As previously indicated, such temperature conditions restrict the use, and types and manners of application of the generally available compositions.

However, an improved artificial snow composition suitable for spraying from an aerosol container or the like has now been discovered and it can be satisfactorily sprayed at temperatures substantially below the previous limit of about 70° F. In this connection, it has been found that the improved composition of this invention can be satisfactorily sprayed at much lower temperatures while providing an excellent flock simulating snow. Accordingly, the utility and commercial acceptability of the artificial snow composition are substantially improved over presently available compositions. Furthermore, the improved utility is economically obtained with commercially available constituents for the composition.

Accordingly, a primary object of the present invention is to provide an improved artificial snow composition and ingredients therefor. A still further object of the invention is the provision of an artificial snow composition capable of providing high quality flock at low cost, and at relatively low temperatures, which composition can be readily dispensed from an aerosol container or the like.

It is also a primary object of the present invention to provide improved ingredients for an artificial snow composition which can be readily sprayed from an aerosol container or the like, said ingredients aiding in the low temperature, snow-making effectiveness of such composition.

2

Further objects and advantages of the present invention will be apparent from a study of the following detailed description.

5 The composition of the present invention basically includes a flocking agent, a fluidizing agent, a propellant, and a binding agent. The fluidizing agent has mutual solubility with the flocking agent, and is believed to provide particle size control for the flocking agent and to effect uniform dispersion of the flocking agent in the composition. As will be indicated hereinafter, the fluidizing agent is a compound having oleophilic groups and groups with affinity for liquid propellant so as to provide certain mixing properties with propellant and oil.

Now referring more specifically to the flocking agent of 15 the present invention, the flocking agent is present in a concentration of between about 1 and about 20 percent by weight of the composition. As used herein the terms "percent" and "parts" are used to mean percent or parts by weight. The flocking agent may be any suitable fatty acid or glyceride which are solid up to temperatures of about 100° F. Accordingly, the fatty acid will be one, or a mixture of two or more fatty acids, having a relatively high molecular weight, that is, fatty acids which have a carbon chain length of at least about 12 carbon atoms, but preferably not more than about 22 carbon atoms. While such fatty acids may be saturated or unsaturated and may contain any suitable subsidiary groups, for example, hydroxy groups or the like, they will usually be saturated rather than unsaturated.

20 30 Particularly effective flocking agents are palmitic acid and stearic acid, especially when utilized together in a mixture in which the palmitic acid accounts for approximately 70 percent by weight of the mixture and the stearic acid approximately 30 percent by weight of the mixture. It will be understood that other mixtures of 25 these two fatty acids and other fatty acids are also suitable, as before indicated.

35 The fluidizing agent coacts with the flocking agent and, in accordance with this invention, is present with the flocking agent at a level of between about 5 percent and about 15 percent by weight of the flocking agent. As before indicated, this fluidizing agent includes oleophilic and propellant-phobic groups, and accordingly, may have emulsifying properties.

40 45 A number of suitable substances are available for use as the fluidizing agent. However, it is preferred that the fluidizing agent be an ester of a short chain (1 to 4 carbon atoms) (polyhydric alcohol) and a long chain (12 to 22 carbon atoms) fatty acid.

50 55 Tests have demonstrated the superior properties of methyl palmitate as the fluidizing agent. Other esters which may be used include ethyl palmitate, methyl stearate, ethyl myristate and methyl oleate. Methyl ricinoleate is also contemplated, as well as methyl and ethyl linoleate. The indicated list of suitable esters is not intended to be exhaustive and equivalent compounds will be readily suggested to those skilled in the art.

60 It should be understood that a compatible mixture of two or more of the indicated fluidizing agents can be utilized, so long as the fluidizing agent comprises between about 1 and about 20 percent by weight of the flocking agent.

65 70 The mixture of the flocking agent and the fluidizing agent is to a large extent responsible for the substantial reduction in the minimum temperature at which the artificial snow composition can be used effectively from an aerosol container. Thus, if an artificial composition were utilized which did not include the indicated mixture, such as that described, of these agents, the improved results with respect to the minimum temperature of effective operation of the artificial snow composition would be

lost. Moreover, if either ingredient of the mixture were used alone, the effective results would not be obtained.

The binding agent is, for the purposes of the present invention, any suitable resin binder such as those utilized in conventional artificial snow compositions. In most instances the binding agent will be a synthetic resinous polymer, such as polyvinyl acetate, the methacrylates or the like.

The binding agent will be present at a level of between .25 percent and about 2 percent of the final snow composition. The level is desirably minimized to reduce cost and to maintain the fluidity of the composition at low temperatures while, at the same time providing bonding properties. The binding agent should be white or translucent so as not to affect the snow effect of the composition.

A solvent for the bonding agent which is miscible with or dispersible in the flocking agent is also present in the composition. The concentration of the solvent will depend primarily upon the amount of resin which needs to be solubilized and the solvent power of the particular solvent. The amount and selection of the solvent is within the skill of the art. However, the solvent should not be inflammable or deleterious to humans, paint, or other things which may be sprayed. A particularly satisfactory solvent is methylene chloride.

As before indicated, the composition of the invention further comprises a propellant. It is contemplated that propellants conventionally used with aerosol containers will be used in the composition of this invention. Of course, such propellant should be non-toxic and be capable of spraying the composition. Propellants particularly contemplated in connection with this invention are Freons which are recognized in the art as a class of polyhalogenated lower alkanes. Since these compounds are so well known in the art for propellants in aerosol containers, a further description of these compounds is not believed to be required. While other propelling gases may be used, such as nitrogen and carbon dioxide, such propellants are generally not satisfactory as propellants of the composition of this invention.

Sufficient propellant should be used to effect the spraying of the contents in the aerosol container and, in general, the propellant will comprise from about 60 percent to about 90 percent of the composition of the invention.

Example I

The composition of this invention is prepared by first preparing a blend of fatty materials comprising methyl palmitate and a fatty acid mixture comprising palmitic acid and stearic acid. The methyl palmitate comprises about 10 percent of the blend, the palmitic acid comprises about 63 percent of the blend, and the stearic acid comprises about 27 percent of the blend.

Twelve pounds of this blend of fatty materials is combined with three pounds of a solubilized resin solution. The resin solution is prepared by mixing one pound of polyvinyl acetate with two pounds of methylene chloride. The fatty materials and this solubilized resin may be mixed together. On the other hand, in commercial operations, four parts of the fatty components are introduced into an aerosol container and, to this is added one part of the resin solution. The container is then filled with about 21 parts of a Freon propellant, under pressure, in accordance with the usual practice in the art.

This composition, therefore, comprises the following ingredients:

12 percent fatty materials
3 percent resin solution
85 percent Freon propellant

This solution could be sprayed at below 50° F. and set up at about 47° F. As before indicated, presently available commercial compositions become viscous and unsprayable at considerably higher temperatures.

Example II

As another example of this invention, the same ingredients are used as specified in Example I, except that ethyl palmitate is substituted for the methyl palmitate in the manufacture of the compound.

Example III

As another example of this invention, the same formula as in Example I is used, except that methyl stearate is utilized in place of the methyl palmitate.

Example IV

In accordance with this example, the same ingredients are employed as in Example I, except that the fatty materials comprise palmitic acid alone, in place of a mixture of stearic and palmitic acids.

Example V

In accordance with this example, the same ingredients are used as in Example I, except that the fatty materials comprise about 12 percent of methyl palmitate, about 62 percent palmitic acid and about 26 percent stearic acid.

In using the composition of the invention, the composition is discharged from the aerosol container through the usual nozzle on to a surface which is to be decorated. This is in accord with the well known practice for effecting decorations with these artificial snows.

As before indicated, a principal feature of this invention is in the utilization of a particular mixture of fatty materials, the mixture comprising fatty acids in combination with esters having hydrophilic and oleophilic groups. Such ester not only provides improved dispersion and distribution of the fatty acid product, but, in addition, provides fluidity to the product at a much lower temperature than is provided by the artificial snow products presently available.

It will be apparent from the foregoing that various modifications in the composition may be made, within the scope of this invention, which are within the skill of the art as contemplated.

The various features of this invention which are believed to be new are set forth in the following claims.

We claim:

1. An improved artificial snow composition comprising, in combination, a flocking agent comprising between about 1 percent and about 20 percent of said composition, said flocking agent including a long chain fatty acid having from between 12 and 22 carbon atoms, a fluidizing agent in an amount of between about 1 percent and 20 percent of said flocking agent, said fluidizing agent being an ester of a short chain polyol having from 1 to 4 carbon atoms and a long chain fatty acid having from 12 to 22 carbon atoms, a propellant comprising polyhalogenated lower alkanes in an amount of about 60 percent and 90 percent of said composition, a binding agent comprising synthetic resin polymer in an amount of about between .25 percent and 2 percent of said composition, and a solvent for said binding agent which is miscible with said flocking agent.

2. An improved artificial snow composition comprising, in combination, a flocking agent comprising between about 1 percent and about 20 percent of said composition, said flocking agent comprising a mixture of palmitic acid and stearic acid, a fluidizing agent in an amount of between about 1 percent and 20 percent of said flocking agent, said fluidizing agent being methyl palmitate, a polyhalogenated lower alkane refrigerant propellant in an amount of about 60 percent and 90 percent of said composition, polyvinylacetate in an amount of about between .25 percent and 2 percent of said composition, and a solvent for said binding agent which is miscible with said flocking agent.

3. An improved artificial snow composition comprising

ing, in combination, a mixture of palmitic acid and stearic acid, the palmitic acid comprising about 70 percent and the stearic acid comprising about 30 percent of said mixture, said mixture comprising about 12 percent of said composition, a fluidizing agent in an amount of about 10 percent of said mixture of fatty acids, said fluidizing agent being methyl palmitate, a propellant comprising polyhalogenated lower alkanes in an amount of about 85 percent of said composition, polyvinyl acetate in an

amount of about 1 percent of said composition, and methylene chloride in an amount of about 2 percent of said composition for dissolving said polyvinyl acetate.
